(57) **CLAIM**

The ornamental design for a surgical drape with a retraction member, as shown and described.

DESCRIPTION

FIG. 1 is a perspective view of an embodiment showing the new design for an surgical drape with a retraction member; FIG. 2 is a plan view of a front surface of the embodiment of FIG. 1;

FIG. 3 is a plan view of a back surface of the embodiment of FIG. 1;

FIG. 4 is a plan view of a top edge and bottom edge of the embodiment of FIG. 1;

FIG. 5 is a plan view of a left-side edge and right-side edge of the embodiment of FIG. 1;

FIG. 6 is a perspective view of an embodiment showing the new design for an surgical drape with opposing retraction members;

FIG. 7 is a plan view of a front surface of the embodiment of FIG. 6;

FIG. 8 is a plan view of a back surface of the embodiment of FIG. 6;

FIG. 9 is a plan view of a top edge and bottom edge of the embodiment of FIG. 6;

FIG. 10 is a plan view of a left-side edge and right-side edge of the embodiment of FIG. 6;

FIG. 11 is a perspective view of an embodiment showing the new design for a two-piece surgical drape with a retraction member;

FIG. 12 is a plan view of a front surface of the embodiment of FIG. 11;

FIG. 13 is a plan view of a back surface of the embodiment of FIG. 11;

FIG. 14 is a plan view of a top edge and bottom edge of the embodiment of FIG. 11;

FIG. 15 is a plan view of a left-side edge and right-side edge of the embodiment of FIG. 11;

FIG. 16 is a perspective view of an embodiment showing the new design for a two-piece surgical drape with opposing retraction members;

(Continued)

FIG. 17 is a plan view of a front surface of the embodiment of FIG. 16;
 FIG. 18 is a plan view of a back surface of the embodiment of FIG. 16;
 FIG. 19 is a plan view of a top edge and bottom edge of the embodiment of FIG. 16; and,
 FIG. 20 is a plan view of a left-side edge and right-side edge of the embodiment of FIG. 16.
 In FIGS. 1, 2, 6, 7, 11, 12, 16, 17, the broken line outside of the claimed surfaces is for the purpose of illustrating portions of the article that form no part of the claim.
